LLP(57) **CLAIM**

The ornamental design for a lever, as shown and described.

DESCRIPTION

FIG. 1 is a perspective view of a lever of the new design;
FIG. 2 is a front elevational view of the lever of FIG. 1;
FIG. 3 is a rear elevational view of the lever of FIG. 1;
FIG. 4 is a left side elevational view of the lever of FIG. 1;
FIG. 5 is a right side elevational view of the lever of FIG. 1;
and,

FIG. 6 is a top plan view of the lever of FIG. 1, the bottom plan view being a mirror image thereof.

The portions of the Figures shown in broken lines are not part of the claimed design and are for illustration only.
